TRAM RAIL CONSTRUCTION

James Bently Forker, Shaker Heights, Ohio, assignor to The Forker Corporation, Cleveland, Ohio, a corporation of Ohio

Application November 2, 1949, Serial No. 125,083

5 Claims. (Cl. 191—23)

1

This invention relates to an electrification system for a tramrail, traveling crane or the like and, more particularly, to the manner of mounting, shielding and energizing the conductor or conductors forming part of the system.

In any system of tramrail or crane electrification, it is necessary that the conductors be so located that they are exposed to the current collectors, which as a rule are mounted on a trolley cooperating with the track. It is desirable that the conductors be shielded to preclude or at least minimize the likelihood of accidental contact with the conductors, which ordinarily are substantially coextensive in length with the rail. So far as practicable, the shielding should provide protection from rain, ice and dirt and yet permit ventilation for the dissipation of heat. At the same time, it is important that arcing between conductors and between the conductors and the other parts of the system, particularly the shielding, be obviated. These requirements make it difficult to design an electrification system that is at once safe to use and simple to make, install and maintain.

The present invention has for its object to attain, and does in fact attain, these and other desirable ends that will be apparent to those skilled in the art from the description which follows and from the accompanying drawings.

Among other things, objects of the invention include the provision of an electrification system that may without significant loss of headroom be applied to existing structures not previously electrified, that will work equally well inside and outdoors, and that in the event of local building fire will not permit live conductors to fall to the floor but will continue for a prolonged period of time to support them at the level at which installed. Other objects include the provision of an electrification system for a tramrail permitting of the use of tramrail switches characterized by reduced overall dimensions and small throw as compared with switches of the type required where the electrification system is disposed asymmetrically of the tramrail. These and other objects of the invention are attained by providing an electrification system located immediately below the track in a tramrail, traveling crane or the like in which the conductors and shielding are supported by and positioned centrally of the track.

In the drawings, Figure 1 is a side elevation of a tramrail showing a preferred form of lead-in assembly for the shielded electrification system forming part of the present invention. Fig-

2

ure 2 is an end elevation from the right in Figure 1, the current collector normally forming part of the two-wheel trolley therein shown being omitted in the interests of clarity. Figure 5 is a cross section through the lower part of the rail, the shielding, and the spacer assembly. Figure 4 is an end elevation, on a reduced scale, of a two-wheel trolley with a conventionalized collecting shoe shown therein, the rail, shielding and conductors appearing in section. Figure 5 is a plan of a modified form of shielding usable in lieu of the shielding illustrated in Figures 1 to 4, inclusive. Figure 6 is a plan of the shielding in Figure 5 when bent to conform to a track curvature of short radius, as in a switch system. Figure 7 is a perspective on a somewhat smaller scale of a section of curved track provided with shielding of the type illustrated in Figures 5 and 6.

20 The tramrail shown in Figures 1 to 4 of the drawings includes a rail 1 which as shown is a T-rail but which, if desired, may take the form of a beam rail. Such T-rail, used for short spans, is characterized by a relatively narrow top flange 2, has the usual wide bottom flange 3, and is suspended from the ceiling or some other convenient support by means of hanger 4. Cooperating with rail 1 is a trolley, which ordinarily will be a four-wheel or eight-wheel trolley having a longitudinally extending load bar but which may be and for simplicity is represented as being a two-wheel trolley made up of a yoke 5 and two trolley wheels 6a and 6b, the trolley wheels riding on bottom flange 3 of rail 1. To prevent the trolley from riding off rail 1 at the end thereof, abutments 7a and 7b are provided which abutments act as stops for trolley wheels 6a and 6b. Abutments 7a and 7b take the form of L-shaped members the shanks of which are made fast, as by screws or bolts, to the web of the rail.

40 Located immediately below and symmetrically of bottom flange 3 of rail 1 is a stiffened sheet metal shield, preferably of ferrous metal, taking the form of a longitudinally extending U-shaped housing 8. Such housing is fastened at intervals along its length to the under side of the bottom flange by spot or arc welding. Where arc welding is used, the welds make contact as shown in Figures 2 and 3 both with housing 8 and bottom flange 3 of rail 1. Housing 8 is not coextensive with rail 1 but continues for a short distance beyond the end of the rail, this in order to provide clearance for the current collector and room above the housing for the lead-in assembly shown at the right in Figure 1.

Where it projects beyond rail 1, housing 8 is provided with a circular aperture (not shown) through which a rigid conduit 9 extends to a point within housing 8 from a point at or above the level of narrow flange 2 of rail 1. The part of conduit 9 in apposition to narrow flange 2 of rail 1 is held in place by means of a metal strap 10 that is welded, bolted or otherwise affixed to the flange 2, the upper end of conduit 9 projecting into a conduit box 11 through a circular opening (not shown) in strap 10. Preferably, the ends of conduit 9 which enter housing 8 and conduit box 11 are externally threaded. By means of nuts cooperating as shown in Figures 1 and 2 with the threaded portions thereof, conduit 9 is held against movement.

Current is supplied to conduit box 11 from a conventional flexible conduit 12. From conduit box 11 three separate leads 13 extend downward into rigid conduit 9 and thence into housing 8. At their lower ends, leads 13 are provided with connectors 14 of conventional shape which are bolted or otherwise fastened to three conductor bars 15, 16 and 17, located as shown in Figures 2, 3 and 4 of the drawings. To minimize the possibility of arcing, conductor bars 15, 16 and 17 are spaced well apart from each other and well removed from the nearest interior surfaces of housing 8. As shown in Figures 1 to 4, housing 8 extends downward to a level well below the bottoms of conductor bars 15, 16 and 17, thus substantially reducing the likelihood of occasional accidental contact with the conductor bars but leaving the bottom of housing 8 open for purposes of ventilation and reception of the current collector on the cooperating trolley.

As shown in Figures 2, 3 and 4, housing 8 is generally channel-shaped, base 20 thereof being somewhat narrower than but making extensive surface contact with the wide underside of bottom flange 3 of rail 1. Base 20 is flanked by slants 21 and 22 which carry housing 8 laterally beyond the outermost surfaces of bottom flange 3. Slants 21 and 22 terminate below the outer faces of trolley wheels 6a and 6b, housing 8 continuing downward therefrom to provide two depending skirts or skirt-like portions, designated 23 and 24, which serve as side walls. At their lowermost portions, which are well below the lowermost surfaces of conductor bars 15, 16 and 17, side walls 23 and 24 are reversely bent as shown in Figures 2, 3 and 4 to form inside wearing strips 25 and 26. Wearing strips 25 and 26, which are coextensive in length with housing 8, serve to stiffen side walls 23 and 24 in the region in which the current collector may come into contact therewith, as, for example, in the event of rocking of the trolley, and also serve as guides for the current collector. If desired, the reversely bent portions may be spot welded to side walls 23 and 24 to prevent opening up of the wearing strips.

Conductor bars 15, 16 and 17 are shown as held in place within housing 8 and in the desired spaced relation to each other by means of transversely extending metal rivets which bridge the channel in housing 8 and which, in the sense that they tend to position opposed side walls 23 and 24, may be described as stiffening means.

As best shown in Figures 1 and 3, housing 8 is provided just below slants 21 and 22 with oppositely aligned indentations 27 and 28 in which are received the heads 29 and 30 of rivets 31. The portions of the rivets immediately adjoining heads 29 and 30 thereof pass through central circular openings (not shown) in indentations 27

and 28. Rivets 31, being of metal, must be insulated from conductor bars 15, 16 and 17; accordingly, each rivet is surrounded from end to end thereof by a snugly fitting cylindrical insulator 32 which may be of a phenolic resin ("Micarta") or some other material of suitable dielectric and engineering characteristics. Rivets 31 and insulators 32 pass with little clearance through circular openings (not shown) in conductor bars 15, 16 and 17, which openings are in alignment with each other and with the openings in indentations 27 and 28, all to the end of making possible a rivet-and-spacer assembly of a high degree of rigidity and dielectric strength.

Surrounding each insulator 32 are four spacers 33, likewise of phenolic resin ("Micarta") or some similar insulating material, which are so proportioned in respect of diameter as to fit snugly outside insulators 32 and so proportioned in respect of length as to locate conductors 15, 16 and 17 in the desired relationship to each other and to housing 8. Like insulators 32, spacers 33 are cylindrical, although individually much shorter in length. Together with conductor bars 15, 16 and 17, spacers 33 fill the space between opposed indented portions in side walls 23 and 24. Thus they serve to preclude the possibility of lateral movement of conductor bars 15, 16 and 17 within housing 8.

The assembly shown in cross section in Figure 3 occurs at regular intervals longitudinally of housing 8, the distance separating them being determined by the size and weight of the conductor bars and the dimensions of the housing. The assembly closest to the end of rail 1 appearing in Figure 1 of the drawings is so located with respect thereto as to permit the connectors 14 and the other elements of the electrical coupling means used for the purpose of energizing conductor bars 15, 16 and 17 to extend for a convenient distance inward along the underside of bottom flange 3 of rail 1. In the event of local building fire, these assemblies and particularly the rivets forming part thereof serve to hold up the live conductor bars long enough to minimize the likelihood of additional damage to property and/or injury to personnel arising out of displacement of the conductor bars themselves.

Figure 4 shows in detail the manner in which conductor bars 15, 16 and 17 make contact with the collecting shoes forming part of a current collector 35 mounted on the yoke 5 of the trolley cooperating with rail 1. The current collector 35, the construction of which is not important for present purposes and which is therefore shown in conventionalized fashion, embodies three spring-loaded collecting shoes 36 which underlie and make contact with conductor bars 15, 16 and 17. Extending downward from collecting shoes 36 are three leads 37 that are grouped within a cable 38 passing through a hollow king pin 39 forming part of trolley yoke 5. If, rather than a two-wheel trolley of the type shown in the drawings, a four-wheel trolley is employed, the two yoke assemblies will be connected by a load bar extending from the king pin of one yoke assembly to the king pin of the other, in which case the current collector will of course be mounted above the level of the top of the load bar in such manner as to preclude mutual interference between them.

The power drawn from conductor bars 15, 16 and 17 by means of current collector 35 may be used for energizing a motor incorporated in the trolley; in such case, the motor may be used, if desired, for moving the trolley itself. In many

instances, the electrification system will have three conductors such as conductor bars 15, 16 and 17; however, in special cases, more than three may be required and in other only two will be necessary. The shape of housing 8 will be determined in large part by the number and location of the conductor bars and to some extent by the size and shape of the current collector.

The shielded electrification system so far described includes two skirts or skirt-like portions interconnected by slants 21 and 22 and the horizontally extending base 20. It is not necessary that housing 8 be formed integrally as shown in Figures 1 to 4; instead, it may, if desired, be made up of two independent skirts or skirt-like portions which are separately affixed in some suitable way to the under side of bottom flange 3 of rail 1. In such a case, base 20 of housing 8 may be largely or entirely supplanted by a gap or space extending substantially from one to the other of the two slants or even from one to the other of the two skirt-like portions. A construction in which the shielding is in two spaced parts 41a and 41b is illustrated in Figure 5, which shows the two parts as seen from above but with the rail itself removed. In addition to being made up of two spaced parts 41a and 41b separated from each other by a longitudinally extending gap, the shielding shown in Figure 5 is characterized by a multiplicity of transversely extending notches or slots 43a and 43b.

Slots 43a and 43b preferably extend through two horizontally extending flange-like portions 42a and 42b corresponding to base 20 by which the two skirt-like members 41a and 41b are made fast, as by spot or arc welding, to the under face of bottom flange 3 of rail 1 and thence across slants 44a and 44b, at the outer limits of which slots 43a and 43b may conveniently terminate. Below slants 44a and 44b, side walls 45a and 45b are imperforate except where apertures are provided as previously described for reception of the ends of the rivet-and-spacer assemblies shown in cross section in Figure 3. As in the case of the shielding shown in Figures 2, 3 and 4, the lowermost portions of side walls 45a and 45b are reversely bent to provide interior wearing strips 46a and 46b.

In addition to permitting ventilation and attendant dissipation of heat through slots 43a and 43b, the two-part shielding shown in Figure 5 has the further advantage that it can readily be bent as illustrated in Figure 6 to conform to a track curvature of relatively short radius such as that used, for example, for switching purposes. If so bent, the slots in one part diverge or open up at their outer ends while those in the opposed part converge or narrow down at their outer ends as indicated in Figure 6. As therein illustrated, slots in member 41a, although originally of uniform width, have opened up at their ends so as to present relatively wide spaces 47 adjoining the gap between the two parts. The slots in opposed member 41b, although originally of uniform dimensions, have narrowed down at their ends as indicated at 48 to a point where much of the original opening has disappeared.

In this manner, members 41a and 41b may be bent to permit the shielding to accommodate itself, within reasonable limits, to a track curvature of relatively small radius. After bending, the members may be spot or arc welded or otherwise fastened to the under surface of bottom flange 3 of rail 1, following which conductor bars 15, 16 and 17 may be mounted thereon by means

of transversely extending rivet-and-spacer assemblies of the kind previously described. If desired, the rivet-and-spacer assemblies may be introduced before the shielding is affixed to rail 1, thus facilitating handling of the shielding as a unit notwithstanding the fact that the shielding itself is not integral but in two major parts. In either case, the resulting arrangement of parts is shown in Figure 7 in which, for the sake of clarity, the current collector has been omitted from the trolley.

It is apparent from the foregoing that important advantages attach to the use in a tram-rail, traveling crane or the like of shielding of the kinds described. One such advantage is the fact that the shielding may, if desired, be formed of a single piece of sheet metal which is folded, bent and indented to the extent necessary to provide a construction of the kind illustrated in Figures 1 to 4, inclusive. Such shielding may, if desired, be perforated at intervals to provide for the dissipation of heat by ventilation, although in general the open construction characterising the bottom of the housing 8 makes for efficient ventilation without adding such apertures. If, for reasons applicable to a particular installation; e. g., the necessity of bending the shielding to conform to a track curvature, it is desirable to make the shielding in two parts, this can readily be done: such parts may conveniently be interchangeable until such time as they are bent as above described to introduce a lateral curvature into the shielding itself. In either case, the shielding may be attached to the track in simple fashion and in a relatively short time, usually by conventional methods.

In addition to these advantages, a further advantage follows from the fact that the shielding is located below the track with the conductor bars spaced symmetrically of the track. With this arrangement, if the trolley is turned around on the supporting structure, as is possible with certain switching combinations, the collecting shoes on the current collector nevertheless line up properly with the conductor bars. To correct for resulting phase reversal, it is desirable to add a transformer to the system, connecting the primary side of the transformer to the main power source. On the secondary side, one of the three phases is grounded and also connected to the tramrail track which has electrically bonded joints, another is connected to the two outside conductor bars, and the third is connected to the middle conductor bar. For the hoist and trolley motors, the proper phase is grounded to the trolley which rolls on the tramrail track, a second phase is connected to the two outside current collecting shoes, and the third is connected to the middle collecting shoe. By this method, phase reversals are eliminated and the advantages of having the electrification system located below the track and symmetrically of the center line of the track are fully realized.

It is evident that numerous changes in relationships, proportions, construction, and manner of assembly may be made without departing from the spirit of the invention. In lieu of the preferred methods and materials employed as above described, various other methods and materials may be employed: for example, the rivet-and-spacer assemblies may, if desired, be replaced by other stiffening and supporting means that will serve to position the conductor bars at the proper places within the shielding. Although its presence is often desirable, it is not neces-

sary that a wearing strip be provided: this may be omitted by omitting the step of transversely bending the side walls of the housing. Various other changes, including the addition of still other means for ventilating, may be made if desired.

It is intended that the patent shall cover, by summarization in the appended claims, whatever features of patentable novelty reside in the invention.

What is claimed is:

1. A tramrail construction comprising an integrally formed upright metal rail having an upwardly-facing outwardly projecting flange for supporting a trolley on the upwardly facing portion thereof; a channel-shaped metal housing affixed to the bottom of the flange with the base of the channel abutting the bottom of the flange; horizontally extending metal rivets bridging the channel in the housing and projecting through the sides thereof; snugly fitting insulating sleeves extending from one side wall of the channel to the other in surrounding relation to the rivets; spacers of insulating material surrounding the insulating sleeves; and, between the spacers, conductor bars with openings for the rivets and insulating sleeves, each of said conductor bars being separated by an air gap from the base of the channel.

2. A construction as in claim 1 in which the housing is of sheet metal.

10

5

3. A construction as in claim 1 in which the housing is formed of a piece of sheet metal of U-shaped cross-section.

4. A construction as in claim 1 in which the housing is formed of two oppositely facing pieces of sheet metal each of which is C-shaped.

5. A construction as in claim 4 in which the C-shaped pieces are slotted where they abut the bottom of the flange.
